MERCURY VAPOR TUBE

Ruric C. Mason, Wilkinsburg, Pa., assignor to
Westinghouse Electric Corporation, East Pitts-
burgh, Pa., a corporation of Pennsylvania

Application August 6, 1941, Serial No. 405,583

3 Claims. (Cl. 250—27.5)

1

My invention relates to electrical discharge devices and, in particular, to electrical discharge devices embodying an atmosphere of mercury or other vapor.

One object of my invention is to produce a mercury or other vapor electrical discharge device in which the electrical characteristics of the tube are less sensitive to changes in ambient temperature than are those of tubes of the prior art.

Another object of my invention is to provide a mercury or other vapor electrical discharge device which can operate at a relatively low vapor pressure and yet be less affected by electrical "clean-up" than are electrical discharge devices of the prior art operating at similar pressures.

Other objects of my invention will become apparent upon reading the following specification taken in connection with the drawing, in which:

Figure 1 shows a curve connecting vapor pressure and ambient temperature which will be used in the following explanation of my invention;

Fig. 2 shows an electrical discharge device embodying the principles of my invention; and,

Fig. 3 and Fig. 4 show forms of an electrical discharge device alternative to Fig. 2.

Electrical discharge devices of the prior art having thermionically-emissive cathodes, anodes, and frequently having control electrodes, which operate in an atmosphere of mercury or other vapor which is in equilibrium with its liquid at the temperature of some portion of the tube walls, are well known. It is found that such discharge tubes are unsatisfactorily sensitive to changes of the ambient temperature in which the tube operates, or to gradual heating up of the tube walls during operation, by reason of the comparatively rapid variation of vapor pressure with temperature of the liquid. For example, the curve I shows the variation of the pressure P with temperature T of mercury vapor which is in equilibrium with liquid mercury. Thus at temperatures above that corresponding to the ordinate marked *a*, the pressure rises very rapidly with comparatively small variations of temperature, and the rate of this rise increases rapidly as the temperature rises further. The electrical characteristics, such as the curve connecting the anode voltage at which the arc ignites with control-electrode voltage, are materially affected by variations of mercury pressure within the tube. Any rise in the ambient temperature about the tube, or even the heating up of the tube walls during operation, causes a rise in the temperature T of the liquid mercury within the tube, and this results in an increase of the pressure within the tube in corre-

2

spondence with the curve I. As a result, the electrical characteristics of the tube are quite sensitive to variations of the ambient temperature.

I have found that mercury vapor may be adsorbed by a quantity of so-called "activated" carbon, that is to say, carbon prepared in a form in which carbon grains are interspersed with a multitude of fine holes or cavities; and that this adsorption results in an alteration of the curve connecting vapor pressure P of the mercury with ambient temperature or temperature T of the container. This is illustrated by the curves II and III in Fig. 1. The curve II represents the variation of pressure and temperature for carbon which has adsorbed a certain number q_1 of atoms of mercury per gram of carbon, and the curve III represents the variation of pressure with temperature for the same carbon in which a number q_2 of atoms of mercury are adsorbed per gram of carbon, q_2 being greater than q_1 . The curve II may, in fact, be represented by the equation:

$$(1) \quad q_1 = \frac{1.33 \times 10^{15}}{T} P e^{\frac{8900}{T}}$$

where q_1 has the constant value above mentioned, T the temperature in degrees Kelvin, and e the base of Napierian logarithms.

Curve III would be represented by a similar equation in which q_2 replaces q_1 . Such curves may be called isosteres.

It will be noticed that each of the curves II and III intersects the curve I at a certain point; below this point the curve of vapor pressure P is represented by the curve I and at higher temperatures by the curve II or III, as the case may be. It will be further noticed that the rise of pressure with temperature along the curve II is, in general, much less than that along the curve I, which latter represents the pressure variation in a tube containing no activated carbon. The same is true, in general, of the curve III. It thus follows that by including activated carbon in the tube containing mercury, the vapor pressure P and electrical characteristics of the latter will be much less affected by variations of the ambient temperature T than will tubes which contain no activated carbon.

Methods of making activated carbon are well known in the chemical art, so that their detailed description is not necessary here. It is my belief that, in general, the adsorbing power of the carbon for mercury vapor increases as the exposed surface (including the exposed surface within small cavities) is increased for a given weight of carbon. One familiar form of acti-

vated carbon is charcoal, that made by properly carbonizing cocoanut shells being frequently used.

Since the reduced vapor pressure due to the presence of activated carbon in the tube is obtained only at temperatures higher than that corresponding to the intersection of the isostere with the curve I, it is desirable that this intersection shall occur at temperatures below any room temperature likely to be met in practice, or at least below the temperature attained by the walls of the tube in normal operation. The temperature of this intersection point can be varied by varying the quantity of mercury which the activated carbon is permitted to adsorb before it is placed in the tube. The Equation 1 above may be combined with the two following equations to calculate the number of mercury atoms to be adsorbed in the carbon, and also to calculate a theoretical curve connecting pressure P within the tube with ambient or wall temperature T .

A certain number of mercury atoms, will, in general, be present in the tube when it is sealed off after evacuation, and these will obviously be distributed partly as a vapor filling the evacuated space in the tube and partly as mercury atoms adsorbed in the activated carbon. The number of mercury atoms present within the evacuated volume of the tube may be calculated from the equation:

$$(2) \quad N = 3.55 \times 10^{16} PV$$

where V is the volume of the tube in cubic centimeters.

The number of atoms of mercury adsorbed in the activated carbon will be

$$(3) \quad q\omega$$

where ω is the weight of the carbon present in grams, and q is as in Equation 1 above.

Since the number of atoms of mercury in the tube is the sum of those present as a gas in the volume V and those adsorbed in the ω grams of carbon, and this quantity is always constant once the tube has been sealed off, it is possible to write the following equation:

$$(4) \quad q\omega + N = \text{constant}$$

By substituting the value of q given by Equation 1 in Equation 3 there is obviously obtained an equation connecting a pressure P with temperature T which will represent the variation of pressure within the tube and its ambient temperature.

The foregoing equations may be used to design an electrical discharge tube in the following way. When the pressure in a tube during operation rises to too high a value, the control grid loses its effectiveness in controlling mean current flow. Thus the pressure P_u in the tube at its highest expected operating temperature T_u is decided upon in advance by the designer. The lowest temperature T_a at which the tube will have to operate will also be known to the designer, and the isostere should intersect the curve I at a temperature corresponding to T_a ; and this intersection likewise determines the corresponding pressure P_a . By substituting this pressure P_a and the temperature T_a in Equation 1, the number q_a of mercury atoms to be adsorbed per gram of activated carbon at the lowest operating temperature T_a is given. The number q_u of mercury atoms to be adsorbed per gram of activated carbon at the highest temperature T_u and pressure P_u are likewise determinable by sub-

stitution in Equation 1. The volume V of the evacuated space within the tube may be arbitrarily fixed, but once this has been done, this volume V may be substituted with the pressures P_a and P_u just determined from the curve I in Equation 2, and the number of mercury atoms N_a and N_u present within the evacuated space of the tube at the temperatures T_a and T_u may be determined. By substituting q_a , N_a , q_u , N_u in Equation 4 there results an equation

$$(5) \quad q\omega + N_a = \text{constant} = q\omega + N_u$$

which may be solved for ω , the number of grams of activated charcoal to be enclosed in the tube. Physical-chemical tables give the number of atoms of mercury per gram of mercury, so that the required quantity of mercury ($q\omega + N_a$) can thus be calculated and weighed out. The design of the tube, insofar as it relates to the present invention, has thus been determined by the foregoing procedure. Curve IV in Fig. 1 represents the relationship between pressure P and ambient temperature T of a tube, as given by Equation 4.

By using activated carbon the amount of mercury adsorbed just about the intersection of the curve I with that obtained from Equation 3 is large compared to the amount of mercury in the gas phase represented by Equation 2, and this insures that any "clean-up" or disappearance of mercury atoms due to continued use of the tube after manufacture will have only a small effect on the vapor pressure within the tube. In the prior art the attempt has occasionally been made to avoid the rapid pressure-rise characteristic of curve I by using tubes in which no liquid mercury was present. But in these tubes "clean-up" of mercury vapor during the life of the tube has resulted in troublesome variation of the gaseous pressure.

While I have referred to the particular vapor present in the tube as being mercury, it will be recognized that this is only for purposes of illustration. Other vapors are subject to adsorption by activated carbon and their substitution for mercury is within the purview of my invention. The principles which I have illustrated by the foregoing equations apply to vapors generally. It will also be recognized that while I have mentioned activated carbon, there are other substances capable of carrying out the adsorbing effect and these may be substituted when otherwise desirable for the activated carbon I have mentioned.

To illustrate the form of actual tubes capable of embodying my invention, Fig. 2 shows a container 1 which may be of glass or other suitable material and capable of maintaining a vacuum. An anode 2 and a thermionically-emissive cathode 3 of conventional form may be embodied in the tube in ways well known in the electrical discharge tube art. Likewise, a control electrode 4 may be provided.

The annular space surrounding the press through which the cathode and grid leads are sealed may be used as a receptacle for the activated carbon mentioned above.

Figs. 3 and 4 illustrate electrical discharge tubes which are like that shown in Fig. 2, except that each is provided with a side branch or side-pocket 5 in which the activated carbon is contained.

While I have illustrated particular embodiments of my invention, it will be recognized by those skilled in the art that its principles are of

broad application and may be practiced with many different forms of tube.

I claim as my invention:

1. An electrical discharge device comprising a vacuum-tight container having electrodes therein and containing within its walls activated carbon within which is adsorbed a substantial quantity of mercury, the number of atoms of mercury in the tube being less than

$$\frac{1.33 \times 10^{15} \omega P}{T} \epsilon^{\frac{8900}{2T}} + 3.55 \times 10^{16} PV$$

where T is the normal operating temperature of the walls of said discharge device in degrees Kelvin, P is the pressure in millimeters of mercury which corresponds to T on the vapor-pressure v. temperature curve of mercury, ϵ is the base of Napierian logarithms, ω is the number of grams of activated carbon in the container and V is the volume of the container in cubic centimeters.

2. An electrical discharge device comprising a vacuum-tight container having an anode, an electron-emissive cathode and a control electrode therein and containing within its walls activated carbon within which is adsorbed a substantial quantity of mercury, the number of atoms of mercury in the tube being less than

$$\frac{1.33 \times 10^{15} \omega P}{T} \epsilon^{\frac{8900}{2T}} + 3.55 \times 10^{16} PV$$

where T is the normal operating temperature of the walls of said discharge device in degrees Kelvin, P is the pressure in millimeters of mercury which corresponds to T on the vapor-pressure v. temperature curve of mercury, ϵ is the base of Napierian logarithms, ω is the number of grams

of activated carbon in the container, and V is the volume of the container in cubic centimeters.

3. An electrical discharge device comprising a vacuum-tight container having electrodes therein and containing within its walls activated carbon within which is adsorbed a substantial quantity of mercury, the number of atoms of mercury in the tube being about

$$10 \quad \frac{1.33 \times 10^{15} \omega P}{T} \epsilon^{\frac{8900}{2T}} + 3.55 \times 10^{16} PV$$

where T is the normal operating temperature of the walls of said discharge device in degrees Kelvin, P is the pressure in millimeters of mercury which corresponds to T on the vapor-pressure v. temperature curve of mercury, ϵ is the base of Napierian logarithms, ω is the number of grams of activated carbon in the container, and V is the volume of the container in cubic centimeters.
